Clock Cases

Des. 1392

ELIAS INGRAHAM, OF BRISTOL, CONN.

Letters Patent for a Design No. 27; dated Mar. 19, 1861.

SPECIFICATION.

TO ALL WHOM IT MAY CONCERN:

Be it known, that I, ELIAS INGRAHAM, of the town of Bristol, county of Hartford and State of Connecticut, have invented or produced a new and original Design for Clock Case Fronts; and I do hereby declare that the following is a full and exact description thereof, reference being had to the accompanying drawing and to the letters of reference marked thereon.

The nature of my invention and design consists in the application of a semi or half formed bead, running up the two plain sides and round the circular part of the head of a mantle or other clock case.

To enable others skilled in the art to make and use my invention and design, I will proceed to describe the same.

The Drawing.

Fig. 1 is the front view of the clock case front.

" 2, a plan view do.

" 3, a side view do.

The clock case design as herein referred to in figs. 1, 2, 3, is a circular head mantle clock, with a plain band, surface projection A on the front B. This band A projects at right angles from the front B, and is made of a suitable width on the face to receive the half bead D, leaving a plain surface on each side to give it a proper and proportionate appearance; the band A, and the bead B, follow up each side, and continue round the circular head C.

The bead moulding B may be composed of either wood, metal, or composition, the shape and form of the design being the same as shown in drawing figs. 1, 2, 3.

D 1392

U. S. PATENT OFFICE, 1861.—No. 27.

Ingraham's Design for a Clock Case Front.

What I claim as my invention and desire to secure by Letters Patent, is—

The design and arrangement of the projecting surface A, and the half bead B, for clock case fronts, in the manner as herein described and represented in the accompanying drawings.

ELIAS INGRAHAM.
